UNITED STATES PATENT OFFICE

2,472,614

TENSION DEVICE

John A. Pons, Morganton, N. C., assignor to
 'Greensboro Textile Supply Company, Greens-
 boro, N. C., a corporation of North Carolina

Application January 26, 1948, Serial No. 4,449

2 Claims. (Cl. 66—146)

1

This invention relates to tension means for a knitting machine and more especially to a tension means which will clamp the yarn when it is not being fed to the needles and when the yarn is thrown out of operation, the clamping means will be allowed to engage the thread and clamp the same to prevent gradual loosening of the tension in the thread when not in use.

In circular knitting machines there are usually several yarn feed fingers which feed different types of yarn to different parts of the stocking during its formation. When one or more yarn feed fingers are in operation, other yarn feed fingers are raised and thrown to inoperative position and the vibration of the machine usually causes a slackening of the yarn which is not being knitted.

It is an object of this invention to provide clamping means which will be rendered inoperative while the yarn is being knitted and when the yarn feed finger is thrown to inoperative position the clamping means will be allowed to clamp the yarn and prevent a slackening of the tension in the yarn while not being used.

Some of the objects of the invention having been stated, other objects will appear as the description proceeds when taken in connection with the accompanying drawings, in which

Figure 1 is an elevation, partly in section, of a portion of a circular knitting machine showing my invention applied thereto;

Figure 2 is a view similar to the upper portion of Figure 1 but showing a yarn fed finger which is equipped with the clamping means raised to inoperative position and showing the strand clamped;

Figure 3 is an elevation on an enlarged scale and taken along the line 3—3 in Figure 1;

Figure 4 is a top plan view of a portion of a circular knitting machine and being taken along the line 4—4 in Figure 3;

Figure 5 is a transverse sectional view taken along the line 5—5 in Figure 2 but showing the tension disks in elevation and not in section;

Figure 6 is a view mostly in elevation and partly in section with parts broken away and taken along the line 6—6 in Figure 5;

Figure 7 is a sectional plan view taken along the line 7—7 in Figure 1 and showing the clamping means not in section and in non-clamping position;

Figure 8 is a view similar to Figure 6 and taken along the line 8—8 in Figure 7.

Referring more specifically to the drawings, the numeral 10 indicates the needles of a circular

2

knitting machine which has sinkers 11 associated therewith. The knitting machine also has a sinker guide ring 12 and a plurality of push rods 13 and a frame 14 having uprising ears 15 and 16 in which is mounted a bolt 17 surrounded by a sheet metal member 18 having a slot 20 therein in which is hooked one end of tension springs 21, the other ends of the tension springs being secured to yarn feed fingers 22 oscillatably mounted on a transverse pin 23 disposed in uprising portions 25 and 26.

The yarn feed fingers have substantially vertically disposed holes 27 in one end thereof through which strands of yarn 28 are passed to be fed to the needles when the yarn feed fingers are in lowered position such as the nearest one in Figure 1.

The strands 28 are passed through suitable eyes 30 in a plate 31 secured by a screw or screws 32 to a transverse bridge portion 34 connecting the tops of uprising members 25 and 26. The yarn feed fingers 22 have backwardly projecting portions 22a with which a portion of the invention is associated. A knitting machine of this type usually has a suitable star-shaped member having spokes 40 extending therefrom with members 41 for receiving cones of yarn C and the strands 28 are fed from these cones C through suitable eyes 42 and 43 mounted on a member 44 which is also supported by an upright shaft secured on the machine and which is not shown.

It is with this type of mechanism that I provide one or more clamping members for clamping a yarn when not in operation and only one of these clamping means is shown but it is understood that others could be employed, that is one for each of the yarn feed fingers 22. This clamping mechanism comprises a plate 50 secured by means of screws 51 to the horizontal portion 34 bridging the gap between the tops of members 25 and 26. This plate 50 has a right angular portion 53 in which the lower end of plunger 54 is slidably mounted. The plate 50 also has a right angular portion 55 at its upper end in which the plunger 54 is also slidably mounted. There is disposed around the plunger 54 and immediately below the right angular portion 55 a compression spring 56 which has its lower end disposed against a collar 57 adjustably secured on the plunger 54 by means of a set screw 58. Secured to the vertical surface of plate 50, by a screw 49, is an angle clip 52 which also has a right angular portion 59 to which is secured, by means of a screw 60, a bracket 61 which projects upwardly and horizontally into a leg 61a. The lower portion of bracket

61 has an adjustment slot 62 therein through which the screw 60 passes.

Secured in the upright leg of bracket 61 is a bolt 64 by any suitable means such as nuts 65 and 66. This bolt 64 has loosely mounted thereon a pair of tension disks 67 and 68. The bolt 64 has a collar 69 fixed thereon for limiting movement of disk 67 to the left in Figure 3. Disposed around the bolt 64 is a compression spring 70 which has one end fitting against the tension disk 68 and has its other end fitting against a knurled nut 72 which is adjusted in position by means of a knurled lock nut 73, both of which are threadably mounted on the right-hand end of bolt 64 as viewed in Figure 3. The horizontal leg 61a has an eyelet 75 through which the strand of yarn 28 passes on its way from the cone C to one of the yarn feed fingers 22.

The lower end of the plunger 54 is adapted to rest against the rearwardly projecting portion 22a of the yarn feed finger 22 except when the yarn feed finger 22 is in inoperative position at which time the lower end of the plunger 54 might not engage the portion 22a on account of its downward movement being checked by the position of the collar 57 on the plunger 54.

The upper end of the plunger 54 has a pointed portion 54a which, when the yarn feed finger is in raised position, will not be disposed between the tension disks 67 and 68 because the spring 56 will push the plunger 54 downwardly to where the collar 57 will rest on the right angular portion 53, but when the yarn feed finger 22 is thrown into operative position, then its rearwardly projecting portion 22a will engage the lower end of the plunger 54 and raise itself to the position shown in Figures 3 and 8 to enter between the tension disks 67 and 68 and force them apart to thereby cause the tension disks 67 and 68 to fail to clamp the strand of yarn 28 so that it can move unimpeded from the cone C through the yarn feed finger and to the knitting needles, and when the yarn feed finger with which the invention is associated is raised to inoperative position, as the rear finger in Figure 1, then the plunger 54 will be moved downwardly by the spring 56 and the pointed portion 54a will be moved downwardly and will occupy the position shown in Figures 5 and 6 to thus cause the tension disks 67 and 68 to clamp the strand of yarn 28 and prevent its being payed off from the yarn cone C due to the vibration of the machine.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a knitting machine having a pivoted yarn feed finger for feeding yarn to the needles of the knitting machine, a pair of tension disks normally moved toward each other and through which the yarn passes, a plunger having a pointed upper portion adapted to pass between the disks and having a lower portion adapted to be engaged by the end of the yarn feed finger remote from the end which feeds the yarn to the needles, so that upon the yarn feed finger being moved to operative position, the plunger will be moved upwardly to cause its pointed portion to pass between the tension disks to remove any clamping effect on the yarn passing therebetween and when the yarn feed finger is moved to inoperative position the plunger will move downwardly from between the disks to cause the disks to clamp the yarn.
2. In a knitting machine having needles and a plurality of yarn feed fingers pivoted intermediate their ends for feeding yarn to the needles and having a feed eye at one end through which the yarn passes to the needles, said knitting machine having suitable push rods therein for raising the yarn feed fingers, a pair of tension disks mounted above the yarn feed finger and having a plunger provided with a pointed upper end for passing between the tension disks and having a lower end for engaging the end of the yarn feed finger remote from the feed end thereof, tension means for normally urging the plunger downwardly to cause it to follow the remote end of the yarn feed finger, moving of the yarn feed finger to operative position causing the plunger to be raised so that its pointed end will pass between the tension disks to remove any clamping effect from the yarn and movement of the yarn feed finger to inoperative position allowing the tension means on the plunger to force the plunger downwardly to where its pointed end will not be disposed between the tension means and thus allowing the tension means to clamp the yarn while the yarn feed finger is in inoperative or non-feeding position.
